C. KAISER.

MEASURING DEVICE FOR LIQUID CONTAINERS.

APPLICATION FILED MAY 24, 1916.

Patented July 17, 1917.

Inventor
CHARLES KAISER

By *Watson E. Coleman*
Attorney

UNITED STATES PATENT OFFICE.

CHARLES KAISER, OF SAVAGE, MONTANA.

MEASURING DEVICE FOR LIQUID-CONTAINERS.

1,233,791.

Specification of Letters Patent. Patented July 17, 1917.

Application filed May 24, 1916. Serial No. 99,660.

To all whom it may concern:

Be it known that I, CHARLES KAISER, a citizen of the United States, residing at Savage, in the county of Richland and State of Montana, have invented certain new and useful Improvements in Measuring Devices for Liquid-Containers, of which the following is a specification, reference being had to the accompanying drawings.

10 This invention relates to an improved measuring device for liquid containers and has for its primary object to provide an outlet or discharge faucet provided with means whereby the liquid may be discharged in predetermined uniform quantities.

15 It is another and more particular object of the invention to provide a device for the above purpose consisting of an outer cylindrical casing provided with inlet and discharge openings, a longitudinally shiftable measuring cylinder mounted within said casing and having opposed ports, one of which is adapted to register with the inlet port of the outer casing in one position of the cylinder and the other with said discharge port in another position of the cylinder, and manually adjustable means mounted in the cylinder for varying the amount of liquid which may enter the cylinder.

20 25 30 35 It is a further general object of my invention to provide a measuring device for tanks or receptacles which is exceedingly simple and durable in its construction, highly serviceable and convenient for the purposes in view, and which may be manufactured at relatively small cost.

With the above and other objects in view, my invention consists in the novel features of construction, combination and arrangement of parts to be hereinafter more fully described, claimed and illustrated in the accompanying drawing, in which,

40 45 Figure 1 is a perspective view of a portion of a tank or receptacle having my improved measuring device applied thereto;

Fig. 2 is a longitudinal sectional view;

Fig. 3 is a similar view showing the inner cylinder in its discharge position;

Fig. 4 is a perspective view of the outer casing; and

Fig. 5 is a similar view, partly broken away, of the inner cylinder.

Referring in detail to the drawing, 5 designates the wall of a tank or receptacle in which the outer cylindrical casing 6 is

mounted and secured in any preferred manner at a point substantially midway between its ends. This casing is provided upon one side of its outwardly projecting portion with a discharge opening indicated at 7, and upon the relatively opposite side of its inwardly projecting portion with an inlet opening 8. The outer end of this casing 6 is open, and within said casing a cylinder generally indicated by the numeral 9 is longitudinally shiftable, said cylinder projecting beyond the outer open end of the casing 6. Adjacent to its inner end, the cylinder 9 is provided with the diametrically opposed, longitudinally extending openings 10, and upon the inner closed end of said cylinder, at one side thereof, a longitudinally extending arm 11 is formed, said arm being of arcuate shape in cross-section and movable through a slot 12 of similar shape which is formed in the inner end wall of the casing 6 at its outer edge.

In the cylinder 9, a circular head 13 is longitudinally adjustable by means of a screw 14 having rotatable engagement in said head. This screw extends axially through the outer portion of the cylinder and is threaded in any preferred manner in the outer end wall of said cylinder. It will be readily understood that by simply turning this screw, the head 13 may be moved and positioned with respect to the inner end wall of the cylinder 9. A suitable handle, indicated at 15, is fixed to the outer end of the cylinder whereby said cylinder may be readily shifted longitudinally within the casing 6.

In the practical operation of the device, it will be understood that after the head 13 has been adjusted to its desired position, when the cylinder 9 is in the position shown in Fig. 2, the liquid will enter from the tank 5 through the inlet opening 8 of the casing 6 and the opening 10 in the wall of the cylinder which coincides therewith. The extension 11 of said cylinder projecting through the slot 12 in the inner end of the casing, will effectually prevent turning movement of the cylinder or disalignment of the openings 10 with the openings 7 and 8. Thus, it will be seen that the liquid will flow into the space between the adjustable head 13 and the inner end wall of the cylinder 9. In order to discharge the liquid, the cylinder 9 is simply pulled outwardly

so as to register the other of the openings 10 with the discharge opening 7 of the casing 6. The desired quantity of liquid will then flow from the inner cylinder through 5 the discharge opening into a suitable receptacle disposed beneath the same. In this manner, it will be apparent that the quantity of liquid dispensed may be accurately predetermined by the proper adjustment of the head 13, and in successive operations of 10 the device the liquid will be discharged in uniform quantities. The device being of exceedingly simple construction, it will be apparent that the same can be produced at 15 small manufacturing cost and readily applied to the ordinary liquid tank or vessel. As the outwardly projecting portion of the cylinder 9 is entirely closed, it will be seen that the contents of the tank are protected 20 against the entrance of dust or dirt and the device thus maintained in a thoroughly sanitary condition. The invention may, of course, be produced in various sizes, in accordance with the particular purpose for 25 which it is to be used. The several parts may also be easily and quickly assembled or disassembled when desired.

While I have shown and described the preferred form and construction of the various elements employed, it is to be understood that the same are susceptible of considerable modification therein and I, therefore, reserve the privilege of adopting all such legitimate changes as may be fairly 35 embodied within the spirit and scope of the invention as claimed.

Having thus fully described my inven-

tion, what I desire to claim and secure by Letters Patent is:—

The combination with a liquid container, 40 of a cylindrical casing fixed intermediate of its ends in the wall of the container and provided with an inlet port in its inner end portion and an outlet port on the diametrically opposite side of its outer end portion, a cylinder longitudinally shiftable 45 within said casing and having an inner closed end and opposed openings in spaced relation to said end of the cylinder, said cylinder being provided upon its inner end 50 with a longitudinally extending arm, the inner end of said casing being closed and provided with a slot therein to receive said arm whereby turning movement of the cylinder in the casing is prevented, a head longitudinally adjustable in the cylinder with 55 respect to the outer ends of the opposed openings therein, and means for adjusting said head, one of the openings in the cylinder being in registering relation with the inlet opening of the casing in one position of the cylinder to permit the liquid to enter into the space between the inner end of the cylinder and the adjustable head and the other opening of the cylinder registering 60 with the outlet opening of the casing to discharge the liquid in another position of said cylinder.

In testimony whereof I hereunto affix my signature in the presence of two witnesses. 70
CHARLES KAISER.
